ELECTRIC BEAN POT

David L. Painter, Evanston, Ill., assignor to West Bend Aluminum Co., West Bend, Wis., a corporation of Wisconsin

Application May 17, 1950, Serial No. 10,011

Term of patent 14 years

(Cl. D81—10)

To all whom it may concern:

Be it known that I, David L. Painter, a citizen of the United States, residing at Evanston, in the county of Cook and State of Illinois, have invented a new, original, and ornamental Design for an Electric Bean Pot, of which the following is a specification, reference being had to the accompanying drawing, forming part thereof, and in which:

Fig. 1 is a view in side elevation of an electric bean pot embodying my new design, the other side view being identical therewith; and

Fig. 2 is a top plan view thereof.

I claim:

The ornamental design for an electric bean pot, substantially as shown and described.

DAVID L. PAINTER.
